[57] CLAIM

The ornamental design for a roller coater paint tray, as shown and described.

DESCRIPTION

FIG. 1 is a top perspective view of a roller coater paint tray showing my new design.

FIG. 2 is a bottom perspective view taken from the opposite end of the roller coater paint tray of FIG. 1.

FIG. 3 is a top plan view thereof;

FIG. 4 is a sectional view taken along line 4—4 of FIG. 3;

FIG. 5 is a sectional view taken along line 5—5 of FIG. 3;

FIG. 6 is a perspective view of a second embodiment of a roller coater paint tray;

FIG. 7 is a bottom perspective view taken from the opposite end thereof;

FIG. 8 is a top plan view thereof.

FIG. 9 is a sectional view taken along the line 9—9 of FIG. 8.

FIG. 10 is a sectional view taken along the line 10—10 of FIG. 8.

FIG. 3

FIG. 4

FIG. 5

FIG. 8

FIG. 9

FIG. 10
